(57) **CLAIM**

The ornamental design for a mop and bucket set, as shown and described.

DESCRIPTION

FIG. 1 is a front perspective view of the bucket feature of the mop and bucket set, showing my new design;

FIG. 2 is rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the bucket in a separated state;

FIG. 10 is a front perspective view of the mop feature of the mop and bucket set;

FIG. 11 is a rear perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is the mop and bucket set complete.

The broken lines in the drawings illustrate the portions of the mop and bucket set, which form no part of the claimed design.

1 Claim, 18 Drawing Sheets
